[57] CLAIM

The ornamental design for a faucet handle or the like, as shown and described.

DESCRIPTION

FIG. 1 is a perspective view taken from the top, front and right side of a faucet handle or the like showing my new design;

FIG. 2 is a top plan view thereof;

FIG. 3 is a front elevational view thereof, the rear being the same as the front shown;

FIG. 4 is a right side elevational view thereof, the left side being the same as the right side shown; and

FIG. 5 is a bottom plan view thereof.

FIG. 1

FIG. 5

FIG. 4

FIG. 3

FIG. 2
